UNITED STATES PATENT OFFICE.

HERBERT H. WATSON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

FRICITION LET-OFF FOR LOOMS.

Application filed May 4, 1925. Serial No. 27,719.

To all whom it may concern:

Be it known that I, HERBERT H. WATSON, a citizen of the United States, residing at Worcester, in the county of Worcester and 5 State of Massachusetts, have invented a new and useful Friction Let-Off for Looms, of which the following is a specification.

This invention relates to improvements in let-off mechanism for looms and more particularly to a let-off having two friction elements one of which moves with the warp beam and the other of which is normally stationary to resist movement of the beam but is movable manually to reverse the warp 15 beam, the reversing force being transmitted through the friction surfaces. In such devices it is desirable to adjust the friction from a convenient part of the loom, and it is accordingly the principal object of my 20 invention to provide a convenient adjustment for this type of let-off.

Another object of my invention is to provide an adjustable friction let-off which will permit a reversal of the warp beam without 25 altering the adjustment of the friction.

A further object of the invention is to provide a let-off with an expansible friction element which may be varied in size by means of a double acting reciprocable pawl and 30 ratchet mechanism.

A more particular object of the invention is to employ a toggle joint connection between the free ends of an expansible friction element which shall be variable by 35 means of a cam face movable at the will of the weaver to alter the tension on the warp irrespective of the angular position of the friction element.

With these and other objects in view 40 which will appear as the description proceeds, my invention resides in the combination and arrangement of parts hereinafter described and set forth in the claims.

In the accompanying drawings wherein a 45 convenient embodiment of my invention is illustrated,

Fig. 1 is a side elevation of a loom showing my invention applied thereto,

Fig. 2 is an enlarged vertical section on 50 line 2—2 of Fig. 1,

Fig. 3 is a diametral section through the friction device on line 3—3 of Fig. 4,

Fig. 4 is a section taken on line 4—4 of Fig. 3 showing the parts placed to provide relatively low friction,

55

Fig. 5 is a view similar to Fig. 4 but showing the parts in a different position to afford relatively high friction.

Fig. 6 is a detail front elevation taken on line 6—6 of Fig. 1, and showing the method of locking the hand lever by means of which the double acting pawl is actuated,

60

Fig. 7 is an enlarged fragmentary view looking in the direction of arrow 7, Fig. 4, and

65

Fig. 8 is a top plan view of the structure shown in Fig. 7.

Referring more particularly to Figs. 1 and 2 it will be seen that I have provided a loom frame 10 having a lay 11 and a warp beam 12 mounted for rotation on the loom frame. Secured to each end of the warp beam is a gear 13 which meshes with a pinion 14. The warp W is led from the beam 12 around the whip roll 15, thence through harnesses not shown to the forward part of the loom. The matter thus far described is of common construction and forms no part 75 of my invention.

My invention relates more particularly to 80 means for placing tension on the warp W in such a way as to permit adjustment of the tension as well as reversal of the beam by acting on one of the friction elements.

In carrying out my invention I provide a 85 rearwardly extending shaft 20 having a hand wheel 21 thereon and mounted in bearings 22 secured to the loom frame. The rear end of said shaft 20 has secured thereto a worm 23 which meshes with worm teeth 24 formed on one of two drums 24^a which are 90 secured to shaft 25 mounted for rotation on the loom frame 10. Each of said drums 24^a

has an interior friction surface 26 substantially concentric with the shaft 25 and 95 adapted to have frictional contact with a flexible arcuate band 27 the outer surface of which may be provided with leather or other friction material. Said surfaces 26 and bands 27 constitute the friction elements 100

which resist rotation of the warp beam 12. With the exception of the worm teeth 24 the drum and parts associated therewith are identical and a description of one will suffice for both. The intermediate portion of band 27 has secured thereto a pair of guides 28 between which extends a pin 29 extending between the forked end 30 of an arm 31 having a hub 32 loosely mounted on the shaft 25. Pinions 14 are secured to hubs 32 and rotate with the friction bands. The adjacent ends of band 27 are provided with bearings 33 and 34, respectively, to which are pivotally connected the outer ends of links 35 forming a toggle and pivoted together by means of pin 36.

Mounted for free rotation on said pin 36 is a roller 37 which is positioned for engagement with a rotatable pressure member 38 having a series of notches 39 in the outer face thereof of different distances from the axis of the shaft 25. Said pressure member has integral therewith a hub 40 which is freely rotatable on hub 32 and has formed therewith two series of ratchet teeth 41 and 42, respectively, the teeth of one series pointing in a direction opposite to the teeth of the other series. Said series of teeth are spaced to provide a run 43 therebetween which receives a lug 44 depending from a pawl 45 formed on the rear end of the rod 45^a. Said pawl 45 has a pull detent 46 to engage the teeth 41 and a push detent 47 to engage the teeth 42. Said detents are laterally offset so that each cooperates with but one series of teeth and said detents are spaced sufficiently far apart longitudinally so that when the parts are in the position shown in Fig. 4, said detents 46 and 47 are out of the path of the teeth of the series 41 and 42 and do not interfere with free rotation of the hub 40.

In order to actuate the pawls 45 the rods 45^a are each connected to an arm 48 which is secured to shaft 49 extending across the loom. Fastened to said shaft 49 is a third arm 50 which is connected by means of link 51 to arm 52 of the lever 53 pivoted as at 54 to a fixed part of the loom. Lever 53 extends forwardly to provide a convenient hand hold for the operator and is normally received in a notch 55 defined between a pair of lugs 56 formed on a plate 57 bolted or otherwise secured to the frame 10 of the loom. When the lever 53 is in the position shown in Figs. 1 and 6 the pawl 45 will be as shown in Fig. 4 so as to permit uninterrupted rotation of the hub 40.

During the normal operation of the loom the worm 23 prevents rotation of worm teeth 24 holding the drums 24^a in fixed position. As the warp beam 12 rotates in a counter-clockwise direction as shown in Fig. 1 to supply yarn the gears 13 will move therewith and cause pinions 14 to have a right hand rotation as viewed in Fig. 1. Inas-

much as said pinions are fastened to the hub 32 as shown in Fig. 3 the friction members 27 will be required to move also and the warp will be resisted in its movement by the friction existing between said members 27 and the interior friction surfaces 26 of the friction drums 24^a. The pressure members 38 are offset from the pawls 45 and move with the friction bands and the devices associated therewith as a unit about the shaft 25.

When it is desired to vary the pressure between the friction bands 27 and the surfaces 26 the lever 53 will be flexed inwardly and removed from the notch 55 and then raised or lowered to the dotted line position shown in Fig. 1 depending upon whether the friction is to be tightened or released. The lever 53 will be vibrated until roll 37 occupies the notch 39 which provides the proper friction, at which time said lever 53 will be restored to its normal position shown in full lines in Figs. 1 and 6. The bands 27 are sufficiently strong to withstand the lateral thrust of the toggles without buckling and the recesses 39 are of sufficient depth to prevent accidental displacement of the rolls 37. Fig. 5 shows the position the toggle and friction member 38 assume when the pressure has been increased, the pawl 45 being drawn to the right to produce a corresponding motion of the pressure device. It would be necessary to restore the pawl to its mid-position before weaving could be resumed.

From the foregoing it will be seen that I have provided a let-off mechanism having a pair of friction elements one of which moves with the warp beam and the other of which can be moved manually to effect reverse rotation of the beam and that the pressure between said elements can be varied conveniently by means operable from the front of the loom irrespective of the angular position of the friction elements. It will further be seen that the pawl is so constructed that the teeth thereof are out of the path of the ratchets when in normal position so as to permit uninterrupted rotation of the beam and it will further be noted that the toggle is held against accidental upsetting by the pockets 39.

Having thus described my invention it will be apparent that changes and modifications may be made therein by those skilled in the art without departing from the spirit and scope of the invention, and I do not wish to be limited to the details herein disclosed, but what I claim is:

1. In a friction let-off for looms, a warp beam, a friction element movable therewith, a normally stationary friction element coacting with the first element to resist forward movement of the warp beam, means to move the second element to reverse the move-

ment of the warp beam, and means to adjust the pressure between said elements irrespective of the relative angular positions of said elements.

- 5 2. In a friction let-off for looms, a warp beam, a friction element movable therewith, a normally stationary friction element coacting with the first element to resist forward movement of the warp beam, means to move 65
10 the second element to reverse the movement of the warp beam, and means to adjust the pressure between said elements independently of the angular position of said second element.
15 3. In a friction let-off for looms, a warp beam, a friction element movable therewith, a normally stationary friction element to coact with the first element to resist forward movement of the warp beam, said normally 70
20 stationary element being movable from one position to another, means to vary the frictional pressure between the elements in any angular position thereof, and means to move said normally stationary element
25 to effect a reverse movement of the warp beam, said friction elements retaining their relative adjustment during the reverse movement of the beam.
30 4. In a friction let-off for looms, a warp beam, a friction element movable with the warp beam, a normally stationary friction element coacting with the first named element to resist forward movement of the warp beam, manual means for varying the 75
35 position of the normally stationary element to reverse the warp beam, means movable with the first named element to vary the pressure between said elements, and manual means for controlling said adjusting means.
40 5. In a friction let-off for looms, a warp beam, a friction element movable therewith, a second normally stationary friction element coacting with the first named element to resist forward movement of the 80
45 beam, means to vary the pressure of the elements including a toggle, and means movable independently of the friction elements to vary the setting of the toggle, said means normally moving with one of the friction 85
50 elements.
55 6. In a friction let-off for looms, a warp beam, a friction element movable therewith, a normally stationary friction element coacting with the first named element to resist forward movement of the beam and movable to effect reverse movement of the beam, and means to vary the frictional pressure 90
60 between said friction elements, said means including an inclined surface movable about the axis of the first named element, and

means to move said inclined surface independently of the angular positions of the elements.

7. In a friction let-off for looms, a warp beam, a friction element movable therewith, a normally stationary friction element coacting with the first named element to resist forward movement of the beam and movable to effect reverse movement of the beam, means to vary the frictional pressure between said elements, said means including a toggle and an inclined surface movable about the axis of one of said elements, and manually controlled means to move said inclined surface in either direction independently of the angular positions of the elements to vary the frictional pressure between said elements.

8. In a friction let-off for looms, a warp beam, a friction element movable therewith, a normally stationary friction element coacting with the first named element to resist forward movement of the beam and movable to effect a reverse movement of the beam, means to vary the frictional pressure between said elements, said means including a toggle and a rotatable member having an inclined surface to coact with the toggle, two series of ratchet teeth formed on said rotatable member, one series pointing in one direction and the other series pointing in the opposite direction, and a double acting manually controllable pawl having oppositely disposed detents to cooperate with the teeth to move said member in either direction.

9. In a friction let-off for looms, a warp beam, a friction element movable therewith, a normally stationary friction element coacting with the first named element to resist forward movement of the beam and movable to effect a reverse movement of the beam, means to vary the frictional pressure between said elements, said means including a toggle and a rotatable member having an inclined surface to coact with the toggle, two series of ratchet teeth formed on said rotatable member, one series pointing in one direction and the other series pointing in the opposite direction, and a double acting manually controllable pawl having oppositely disposed detents to cooperate with the teeth to move said member in either direction, said detents being 100
105 out of contact with the teeth when said let-off is in operative position.

In testimony whereof I have hereunto affixed my signature.

HERBERT H. WATSON.
